Des. 178,426
Patented July 31, 1956

178,426

PORTABLE ELECTRIC JIG SAW

Robert H. Riley, Jr., and Harry J. Foell, Jr., Towson, Md.,
assignors to The Black & Decker Manufacturing Company,
Towson, Md., a corporation of Maryland

Application December 19, 1955, Serial No. 39,377

Term of patent 14 years

(Cl. D93—3)

Fig. 2

Fig. 1 is a perspective view of a portable electric jig saw embodying our new design taken from a point somewhat above and forward of the left side thereof; and

Fig. 2 is an elevational view of the right side of said saw.

We claim:

The ornamental design for a portable electric jig saw, substantially as shown.
